Robert L. Epstein(57) **CLAIM**

The ornamental design for an earphone case, substantially as shown and described.

DESCRIPTION

FIG. 1 is an isometric view of the earphone case showing the top, front and right side thereof;

FIG. 2 is an isometric view of the earphone case showing the bottom, rear and left side thereof;

FIG. 3 is a front elevation view thereof;

FIG. 4 is a rear elevation view thereof;

FIG. 5 is an elevation view of the left side thereof;

FIG. 6 is an elevation view of the right side thereof;

FIG. 7 is a top plan view thereof; and,

FIG. 8 is a bottom plan view thereof.

The broken lines illustrating a strap in the drawings represent portions of the article that do not form a part of the claimed design. The broken lines adjacent to solid lines in the drawings represent boundaries of the claim and do not form part of the claimed design.
